UNITED STATES PATENT OFFICE.

CHARLES F. SCHOEN, OF FRENCHTOWN, NEW JERSEY, ASSIGNOR OF ONE-HALF TO
WILLIAM J. WEISS, OF FRENCHTOWN, NEW JERSEY.

HUB-BORING MACHINE.

1,045,329.

Specification of Letters Patent.

Patented Nov. 26, 1912.

Application filed April 10, 1912. Serial No. 689,721.

To all whom it may concern:

Be it known that I, CHARLES F. SCHOEN, a citizen of the United States, residing at Frenchtown, in the county of Hunterdon and State of New Jersey, have invented certain new and useful Improvements in Hub-Boring Machines, of which the following is a specification.

My invention relates to improvements in hub boring machines, the object of the invention being to provide an improved machine which will simultaneously bore the spoke receiving sockets in a wheel hub, and will insure the proper positioning of these sockets and will quickly and efficiently perform the work.

A further object is to provide an improved arrangement of drills with improved means for simultaneously turning the drills and moving them longitudinally, whereby they are forced into the hub and provide improved means for holding the hub and adjusting said holding means in accordance with the thickness of the hub.

With these and other objects in view, the invention consists in certain novel features of construction and combinations and arrangements of parts, as will be more fully hereinafter described and pointed out in the claims.

In the accompanying drawings: Figure 1, is a top plan view illustrating my improvements. Fig. 2, is a view in side elevation. Fig. 3, is a view in vertical section. Fig. 4, is a top plan view with the top ring and parts carried thereby removed. Fig. 5, is an inverted plan view of the top ring with the bits removed from the drills. Fig. 6, is a view on an enlarged scale in longitudinal section, on the line 6-6 of Fig. 5. Fig. 7, is a view in cross section through one of the pinions and its shaft. Fig. 8, is a detail perspective view of one of the crank arms 32, and Fig. 9, is a fragmentary view in section on the line 9-9 of Fig. 3.

1, represents a standard integral with a base 2, and having its lower end hollow as shown at 3, while the upper portion of the standard is provided centrally with a cylindrical bore 4 for the reception of a shaft 5 which is adjusted vertically therein by means of a set screw 6.

The upper end of the standard 1 is screw-threaded and screwed into a ring 7. This ring 7 is provided with a circular series of

radially and upwardly projecting arms 10, made integral therewith, and with a ring 11. This ring 11 is adapted to receive thereon an upper ring 12, said rings being secured together by screws 13. The upper ring is provided with a plurality of openings for the screws 13, and also with openings for dowel pins 14, which insure the proper positioning of the ring relative to each other. The upper ring is formed with a concentric circular groove 15, and across this groove a plurality of radially positioned drill sockets 16 extend. These drill sockets have bearings 17 in both walls of the groove 15, and are locked to turn with beveled pinions 18 mounted in the groove 15.

The key 19, which locks the pinion 18 to its shaft 16, is mounted in a relatively long key way 20 in the shaft 16, so that the shaft is allowed longitudinal movement, yet always locked to turn with the pinion.

A spacing washer 21 is provided between the pinion and the outer wall of the groove 15 to sustain the thrust against the pinion. The inner end of each shaft 16 is provided with a set screw 22 for securing the bit 23 in the shaft. On the outer ends of the shaft 16, blocks 24 are provided, and are held between collars 25 so that the shafts are permitted a free turning movement in the blocks. Each block is provided at opposite sides with trunnions 26, and these trunnions are supported in recessed bearings 27 in the upper ends of bifurcated arms 29. The bifurcated arms 29 are keyed to shafts 28, and the latter are supported in parallel ears 30 integral with ring 11. Coiled springs 31 are positioned on the shafts 29, and exert a pressure on said shafts to turn them in a direction to maintain the several drills in their outward position as shown in the several figures of the drawing.

Crank arms 32 are secured to the shafts 28. These crank arms project inwardly toward the ring 11, and each crank arm is provided at its free end with a ring 33 connected to the hooked upper end 34 of a turn buckle 35. The crank arms 32 are located in pairs adjacent each other, and the two turn buckles 35 which connect the arms of a pair, are both connected by links 36 with an eye bolt 37.

The arms 29, shafts 28, and crank arms 32 constitute bell-crank-levers which when moved in one direction cause the drills to

move inwardly and are normally held by the springs 31 in position to hold the drills in their outward position.

The links 36 project through slots 38 in the standard 1, and the eye bolt is positioned centrally in the lower hollow portion 3 of the standard, and projects through a foot lever 39 and is secured by a nut 40.

The foot lever 39 extends through slots 41 in the standard, and is pivotally secured by a pin 42 to a bracket 43 on base 2. When the foot lever 39 is depressed, all of the drills will be simultaneously forced inwardly toward the shaft 5 above referred to. On this shaft 5, above the standard 1, and spaced therefrom by a washer 44, is a pulley 45, and this pulley is adapted to be driven by a belt from any suitable source of power.

The pulley 45 is connected by integral arms 46 with a circular beveled rack 47, and this rack 47 meshes with all of the pinions 18. The upper end of shaft 5 is reduced in diameter as shown at 48 forming a shoulder 49 which is adapted to receive and support the wheel hub to be bored.

In accordance with the thickness of the hub, this shaft 5 is positioned and is secured at any adjustment by means of the set screw 6. When the hub is in position, and the rack 47 is turning so as to transmit a rotary motion to all of the drills, the operator places his foot upon foot lever 39 and depresses the same, causing the several drills to cut into the hub to form the pockets or recesses for the spokes. These pockets or recesses will therefore be of uniform depth, and be properly spaced apart.

The operation can be quickly performed, and a great many hubs may be bored in a short space of time, as it is simply necessary to lift the foot off of lever 39 to allow the springs 31 to withdraw the drills, when a finished hub may be removed and a new one placed in position for drilling.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A machine of the character described, comprising a standard having a central longitudinal bore, a hub supporting shaft adjustably secured in the bore of the standard, a pulley supported on the upper end of the standard and mounted to turn on the shaft, radially and upwardly projecting arms on the upper face of the pulley, a circular

rack fixed to the arms, a ring supported by the standard and larger than the rack, a circular series of radially positioned drills supported in the ring, means for simultaneously moving all of said drills longitudinally, and pinions keyed to the drills and meshing with the rack, substantially as described.

2. A machine of the character described, comprising a standard having a central longitudinal bore, a hub supporting shaft adjustably secured in the bore of the standard, a pulley supported on the upper end of the standard and mounted to turn on the shaft, radially and upwardly projecting arms on the upper face of the pulley, a circular rack fixed to the arms, a ring supported on the standard, a circular series of radially positioned drills supported on said ring, pinions on said drills meshing with the rack and keyed to the drills, whereby the latter are permitted longitudinal movement through the pinions, radially positioned arms fixed to the standard and supporting said ring, bell-crank-levers supported on said arms and engaging the drills, a foot lever projecting through the standard, and connecting devices extending through openings in the standard and connecting the foot lever with the respective bell-crank-levers whereby the depression of the foot lever causes the drills to be moved inwardly simultaneously, substantially as described.

3. A machine of the character described, comprising a standard having a central longitudinal bore, a hub supporting shaft adjustably secured in the bore of the standard, a pulley supported on the upper end of the standard and mounted to turn on the shaft, radially and upwardly projecting arms on the upper face of the pulley, a circular rack fixed to the arms, a ring, a circular series of radially positioned drills supported on said ring, pinions on said drills meshing with the rack and keyed to the drills, whereby the latter are permitted longitudinal movement through the pinions, radially positioned arms fixed to the standard and supporting said ring, bell-crank-levers supported on said arms and engaging the drills, means on the standards for simultaneously operating all of said bell-crank levers, and springs coiled about the pivotal points of said bell-crank-levers exerting pressure on the same to normally hold the drills in their outward position, substantially as described.

In testimony whereof I have signed my name to this specification in the presence of two subscribing witnesses.

CHARLES F. SCHOEN.
